US0D1081729S

(12) **United States Design Patent** (10) Patent No.: **US D1,081,729 S**
(45) Date of Patent: ** Jul. 1, 2025

(54) **INFLATOR**

(71) Applicant: **ILLINOIS TOOL WORKS INC.**,
Glenview, IL (US)

(72) Inventors: **Carey Christopher Costle**, Tucson, AZ
(US); **Brendan Sangster**, San Luis
Obispo, CA (US); **Patrick B. Mallon**,
San Luis Obispo, CA (US)

(73) Assignee: **Illinois Tool Works Inc.**, Glenview, IL
(US)

(**) Term: **15 Years**

(21) Appl. No.: **29/862,189**

(22) Filed: **Dec. 7, 2022**

(51) LOC (15) Cl. **15-02**

(52) U.S. Cl.

USPC **D15/9**

CLAIM

The ornamental design for an inflator, as shown and described.

DESCRIPTION

FIG. 1 is an isometric view of a top, front, and right side of an ornamental design for an inflator;

FIG. 2 is a front elevational view of the inflator of FIG. 1;

FIG. 3 is a rear elevational view of the inflator of FIG. 1;

FIG. 4 is a right side elevational view of the inflator of FIG. 1;

FIG. 5 is a left side elevational view of the inflator of FIG. 1;

FIG. 6 is a top plan view of the inflator of FIG. 1; and,

FIG. 7 is a bottom plan view of the inflator of FIG. 1.

The dash-dash-dash lines are included for the purpose of illustrating portions of the inflator that form no part of the claimed design.

1 Claim, 7 Drawing Sheets
